H. A. W. WOOD

COOLER FOR STEREOTYPE PRINTING PLATES

Filed Nov. 21, 1923

UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

COOLER FOR STEREOTYPE PRINTING PLATES.

Application filed November 21, 1923. Serial No. 676,197.

This invention relates to a cooling device for receiving a curved stereotype printing plate directly from the finisher and supplying it with a spray of water on the inside 5 surface to cool it.

The principal objects of this invention are to provide a more economical way of using the water and avoiding the usual necessity in this type of coolers of allowing the water 10 to run as long as the plate is in the cooler and to provide an improved form of cover for preventing splashing and capable of being manipulated in a very convenient way.

Further objects and advantages of the invention will appear hereinafter.

Reference is to be had to the accompanying drawings in which

Fig. 1 is a side elevation of a finishing machine frame with a preferred embodiment 20 of this invention applied thereto and partly broken away to show the interior in section;

Fig. 2 is a transverse sectional view on the line 2—2 of Fig. 1; and

Fig. 3 is a plan of one side, looking in the 25 direction of the arrow 3 in Fig. 2, showing certain details.

This invention is intended to constitute a part of a combined casting, finishing and cooling machine of that type in which complicated machinery is avoided. The cooler is shown as arranged in such relation to the finishing machine that the plate can be moved from the finishing machine to the cooler horizontally by pushing it along the 30 guides which are provided.

I have shown a cooler comprising primarily a tank 1 cast with integral feet 2 with the assistance of which it is held in place on the end of frame 21 of the finishing 40 machine. Fitted to the tank are two horizontal plate tracks 3 upon which the plate is slid into the cooler in a horizontal direction and by which it is supported. These tracks have inner lips 4 which guard the plate 45 against falling off sideways thereby constituting guides and guards.

Located in a substantially central position within the cooler is a longitudinal water spray tube 5 having perforations 7 disposed

at suitable intervals along the entire length 50 and on the upper half of its circumference. This tube is securely fastened at both ends in hollow headers 6 which serve both as storage reservoirs for the proper distribution of the water and as supporting brackets for the tube 5. Water is supplied to one of the headers 6 by a pipe 11 through a controlling valve 12. This controlling valve is of the type known as a flush valve and is provided with a push button 13 which, when pushed by the operator, permits a predetermined quantity of water to pass through it. After this the supply is cut off automatically so that no more water can flow and the operator does not have to pay any attention to it. This valve is one that is bought on the market and the details of it are not a part of this invention. It involves means for regulating the quantity of water passing through the valve. Although I have used here a known type of valve its application to this particular machine is a matter of material importance. It supplies means for regulating and operating the cooling device without the use of mechanism of any sort except the valve. It is an improvement over the valves that have been used heretofore which have been operated by some moving part of the machine or by the weight of the printing plate 8 itself.

It will be seen that this results in economy in construction and convenience in operation as well as reduction in repairs. It also has another important advantage in that it is set so that just the amount of water necessary is used each time a plate is put in. This results in an important saving in the amount of water over that type of devices in which the valves are regulated by the weight of the plate in the cooler. In those devices any delay in moving the plate causes an unnecessary waste of water. In this case the time element is determined independently of the handling of the plate by the operator.

As will be seen, when the water is turned on by pressing the button 13 it is discharged in the form of a uniform spray all over the inside of the plate 8 which is supported in a

position concentric with the supply pipe 5. This thoroughly cools the plate with a minimum amount of water. The water having accomplished its purpose collects on the bottom of the tank and is drained off through the strainer 9 and drain pipe 10. The strainer is used to prevent stray chips from the finishing operation from clogging the drain.

10 An annoying and detrimental feature of the usual coolers attached directly to the plate making machine is the tendency to spill some of the water upon the operators or on the floor near the machine. For the 15 purpose of avoiding this annoyance I provide a semi-cylindrical sheet metal cover 14 which is fitted into a rectangular cast iron frame 15 having downwardly projecting lips 16 on both sides and at the ends, if desired. 20 This frame overhangs the upper edge of the tank 1 upon which it rests. On account of these lips 16 extending down beyond the points of support, the water that may be splashed against this cover will drip down 25 into the tank 1. The cover 14 completely surrounds the convex surface of the plate so that it is impossible for any water to escape.

This cover has to be raised whenever the 30 plate is moved into or out of the cooler. In order to facilitate the raising of the cover and permit it to be raised from either side, it is constructed as follows: Both sides of the tank 1 are fitted with two lugs 17 cast thereon and on both sides of the cast frame 15 are also cast lugs 18 projecting the same distance from the center but further apart than the lugs 17. The lugs 17 have open topped grooves at the top. The lower ends of the 40 lugs 18 are made in the form of stops 19. Between these lugs 18 are cast integrally, or otherwise secured, cylindrical hinge handles 20. These hinge handles rest in the depressions in the lugs 17 on both sides of the 45 device. Whenever it is desired to raise the cover it can be raised from either side as shown in dotted lines in Fig. 2. It can be moved back to a position in which the stops 19 come against the side of the tank. This 50 makes it readily accessible from either side and results in economy in operation as the operator does not have to go around to the other side at any time for the purpose of introducing or taking out the plate.

55 Although I have illustrated and described a single form of the invention, I am aware of the fact that modifications may be made therein by any person skilled in the art without departing from the scope of the invention as expressed in the claims.

Therefore I do not wish to be limited to all the details of construction herein shown and described, but what I claim is:—

1. In a cooling device for a stereotype

printing plate, the combination with supports for the plates and a tank below the supports for receiving the water, of a spray pipe having spray perforations through its upper surface, a flush valve through which a predetermined amount of water can be discharged into the spray pipe and the supply then cut off automatically, and a removable cover over the trough covering the entire surface of the plate when located on said support.

2. In a cooling device for a curved stereotype printing plate, the combination with a pair of supports for the lower edges of the plate and a tank below the supports for receiving the water discharged against the plate, of a spray pipe located longitudinally and concentrically with respect to the plate when on said supports and having spray perforations through its upper surface, a flush valve through which a predetermined amount of water can be discharged into the spray pipe and the supply then cut off automatically, and a removable cover over the trough covering the entire surface of the plate when located on said supports.

3. The combination with a spray pipe for discharging water against the interior of a stereotype curved printing plate, and means for supporting the plate in a position concentric with respect to said pipe, of a tank 95 below the pipe for collecting the water discharged, a frame resting on the top edges of said tank, and a semi-cylindrical cover fixed to said frame and located concentric with the plate and spray pipe and covering both of them.

4. The combination with a cooling tank for a stereotype printing plate, of a cover to prevent splashing of the water out of the tank, said cover having a rectangular frame 105 at the base adapted to rest on the tank and provided with a pair of longitudinal hinge handles at the sides thereof, said tank being provided with supports for these hinge handles open at the top, whereby the cover can 110 be raised from either side pivoting on the opposite hinge handle.

5. The combination with a cooling tank for a stereotype printing plate, of a cover therefor having a pair of parallel hinge handles at its opposite sides, said tank having lugs with concave depressions for receiving said hinge handles, and a cover for the tank rigidly connected with the hinge handles, whereby the cover can be raised from either side to pivot about the opposite hinge handle to expose the cooling device.

6. The combination with a curved stereotype plate cooling tank, of a cover for the tank, and means on the tank for supporting the cover so that it can be swung upwardly from either side about an axis at the other side.

7. In a cooling device for a curved stereotype printing plate, the combination with a pair of supports for the lower edges of the plate, of a spray pipe located longitudinally and concentrically with respect to the plate when on said supports and spaced from it and having spray perforations through its upper surface, a flush valve, and means whereby a predetermined amount of water can be discharged into the spray pipe ¹⁰ through said valve and the valve then closed automatically.
- 5 In testimony whereof I have hereunto affixed my signature.

HENRY A. WISE WOOD.
